UNITED STATES PATENT OFFICE

ISIDOR ROSENBLATT, OF BROOKLYN, NEW YORK

DESIGN FOR A LIGHTING FIXTURE

Application filed December 11, 1929. Serial No. 33,748. Term of patent 7 years.

To all whom it may concern:

Be it known that I, ISIDOR ROSENBLATT, a citizen of the United States, residing at Brooklyn, in the county of Kings and State of New York, have invented a new, original, and ornamental Design for a Lighting Fixture, of which the following is a specification, reference being had to the accompanying drawing, forming part thereof, in which—

Fig. 1 is a view in perspective showing my new design; and

Fig. 2 is a bottom plan view showing contour.

I claim:

The ornamental design for a lighting fixture, as shown.

ISIDOR ROSENBLATT.
